UNITED STATES PATENT OFFICE.

SAMUEL J. THOMAS, OF EAST WENATCHEE, WASHINGTON.

BOX-MARKER.

1,377,941.

Specification of Letters Patent.

Patented May 10, 1921.

Application filed November 29, 1920. Serial No. 427,031.

To all whom it may concern:

Be it known that I, SAMUEL J. THOMAS, a citizen of the United States, residing at East Wenatchee, in the county of Douglas 5 and State of Washington, have invented new and useful Improvements in Box-Markers, of which the following is a specification.

This invention relates to marking devices, particularly those of the rubber stamp type, 10 and has for its object the provision of an improved device for marking boxes of fruit and the like whereby the name of the shipper, the weight of the contents, the variety of the fruit, the quality thereof, and also 15 the number may be stamped upon the outside of the box so that full information as to the contents may be obtained without opening the same.

An important object is the provision of 20 a device of this character which is so constructed that the markers which indicate the variety and quality are detachable so that they may be replaced with ease.

An additional object is the provision of 25 a device of this character which will be simple and inexpensive in construction, easy to use, a great labor saver, and a general improvement in the art.

With the above and other objects and advantages in view, the invention consists in 30 the details of construction to be hereinafter more fully described and claimed and illustrated in the accompanying drawings in which—

35 Figure 1 is a side elevation of the device,

Fig. 2 is an end view with the end guard plate removed,

Fig. 3 is an elevation of the opposite end,

40 Fig. 4 is a face view of the printing surface,

Fig. 5 is a cross sectional view through the stamping member holding means, and

The remaining figures are detail views.

45 Referring more particularly to the drawings, the numeral 10 designates a substantially rectangular frame which may be preferably formed from a suitable strip of metal bent into shape and fastened or which may, 50 if preferred, be formed as a casting. This frame includes a bar 11 upon which is secured a handle 12 and further includes an extension 13 adjacent the bar 11. The bar 14 opposite the bar 11 is preferably longitudinally curved, as clearly shown, and is

braced with respect to the bar 11 by a cross piece 15.

Secured upon the end of the frame which is provided with the extension 13, is a U-shaped frame 16 secured to the extension and 60 to the end and journaled within this frame 16 is a flanged disk 17 about which is trained a rubber belt 18 which is also trained about the bight portion of the frame 16. This belt 18 carries a series of number stamps, 65 indicated at 19.

Secured upon the longitudinal bar 14 are plates 20 and 21 which carry rubber stamps, one of which has a printing surface giving the name and address of the shipper 70 and the other of which has a printing surface giving the net weight of the contents of a box or crate. Also carried by the bar 14 are detachable stamping members designated by the numerals 22 and 23 and each 75 is formed of a channel-shaped body 24 of thin resilient metal having retaining flanges adapted to be snapped over the edges of the bar 14 so as to hold these members upon the bar. The bar 22 carries a rubber stamp 25 80 having a printing surface giving the variety and name of the fruit and the member 23 carries a stamp 26 having a printing surface giving the quality of the fruit or other commodity. In actual practice a series of 85 members 22 and 23 would be used, depending upon the different qualities and different varieties, as will be readily apparent. The flanges on the bodies 24 prevent these members from slipping off from the bar 14 90 and from moving laterally thereon and in order to prevent longitudinal movement each body 24 is provided with a projection 27 engageable within a corresponding hole 28 in the bar 14. Each member 22 and 23 is 95 furthermore provided with a handle 29 whereby it may be sprung onto or off from the bar when desired.

In the use of the device the proper detachable members 22 and 23 are associated 100 with the bar 14, as above described, and the disk 17 is turned to bring the desired number stamp 19 into alignment with the various printing surfaces of the stamping members on the bar 14. The operator then 105 grasps the handle 12 and presses the printing surface onto or rubs it across a suitable ink pad or other device after which the device is so positioned that the printing surface will be engaged upon the box or crate 110

to be marked, the device being rocked upon its curved edge, as will be clearly apparent.

In actual practice it may be advisable to provide guard plates 30 for the disk 17 5 and rubber belt thereon so as to protect the same against injury and to prevent the belt from slipping off.

From the foregoing description and a study of the drawings it will be apparent 10 that I have thus provided a very simply constructed and easily operated marking device for boxes or crates which is easily changeable to apply different markings and which will be a great time and labor saver 15 to the shipper as well as a convenience to the purchaser or inspector of the article stamped as it provides upon the outside of the crate full data as to the contents.

While I have shown and described the 20 preferred embodiment of my invention, it is of course to be understood that I reserve the right to make such changes in the form, construction, and arrangement of parts as will not depart from the spirit of the invention or the scope of the subjoined claims.

Having thus described my invention, I 25 claim:

1. A stamping device comprising a frame

provided with a handle, a plurality of printing members rigidly secured upon the opposite side of the frame from the handle, and a plurality of printing members detachably connected with the frame and each including a channel-shaped body of resilient material having side flanges adapted to 30 snap over and engage upon the edges of said side of the frame, printing members carried by each of said channel-shaped members, and a handle on each channel-shaped member whereby the flanges thereof may be 35 sprung.

2. In a device of the character described including a bar, printing members rigidly secured upon said bar, and other printing members detachably mounted upon the bar 40 and each including a channel-shaped body of resilient material carrying a printing member and having side flanges adapted to snap over the edges of the bar, a handle on each of said channel-shaped members 45 whereby to spring the flanges, and a projection on the inner side of each channel-shaped member, the bar being provided with a hole for the reception of said projection.

In testimony whereof I affix my signature. 50
SAMUEL J. THOMAS.
